US00D704764S

(12) **United States Design Patent**
Markovitz et al.

(10) **Patent No.:** **US D704,764 S**
(b4) **Date of Patent:** **** May 13, 2014**

(54) **EYEGGLASSES**(71) Applicants: **Aaron Markovitz**, New York, NY (US);
Artiss Akarra, Johnston, RI (US)(72) Inventors: **Aaron Markovitz**, New York, NY (US);
Artiss Akarra, Johnston, RI (US)(73) Assignee: **Cross Optical Group, Inc.**, Daytona Beach, FL (US)(**) Term: **14 Years**(21) Appl. No.: **29/452,558**(22) Filed: **Apr. 18, 2013**(51) LOC (10) Cl. **16-06**

(52) U.S. Cl.

USPC ..... **D16/315**; D16/335(58) **Field of Classification Search**USPC D16/101, 300–342, 900; D29/109–110;

(57) **CLAIM**

The ornamental design for eyeglasses, as shown and described.

DESCRIPTION

FIG. 1 is a front view illustrating our design for eyeglasses;
FIG. 2 is a top plan view thereof;
FIG. 3 is a left side view thereof; the right side being a mirror image thereof;
FIG. 4 is a front perspective view thereof;
FIG. 5 is a rear view thereof; and,
FIG. 6 is a bottom view thereof.
